UNITED STATES PATENT OFFICE.

EUGENE A. MURPHY, EDWARD Z. LEWIS, AND WALTER V. WILSON, OF CHICAGO,
ILLINOIS.

RETURN-ENVELOP.

1,216,347.

Specification of Letters Patent. Patented Feb. 20, 1917.

Application filed October 9, 1916. Serial No. 124,497.

To all whom it may concern:

Be it known that we, EUGENE A. MURPHY, EDWARD Z. LEWIS, and WALTER V. WILSON, citizens of the United States, and residents 5 of Chicago, in the county of Cook and State of Illinois, have invented certain new and useful Improvements in Return-Envelops; and we do hereby declare that the following is a full, clear, and exact description thereof, 10 reference being had to the accompanying drawings, and to the letters of reference marked thereon, which form a part of this specification.

This invention relates to improvements 15 in return envelopes and consists of the matters hereinafter described and more particularly pointed out in the appended claim.

The object of the invention is to produce 20 an envelop which may be used for sending papers to one address, the address appearing 25 on the flap when it is folded in the normal fashion, outside of the envelop, and for the return or forwarding of the papers to another address which is printed on the 30 envelop in the space normally covered by the flap and which is disclosed to view when the flap is folded within the envelop.

The invention embodies certain novel features of construction by means of which 35 the flap is properly secured in place to retain the papers in the envelop, when the flap is in either of its positions.

In the drawings:

Figure 1 is a perspective view of our im- 40 proved envelop, showing the flap folded upon the outside thereof and secured in that position.

Fig. 2 is a perspective view of the envelop with the flap folded within the envelop and 45 secured in that position.

Fig. 3 is a partial transverse sectional view of the envelop in the plane indicated by the line 3-3 of Fig. 1.

Fig. 4 is a similar sectional view in the 45 plane indicated by the line 4-4 of Fig. 2.

Fig. 5 is a plan view of a sheet, cut and scored to form the envelop.

Referring now to that embodiment of our invention illustrated in the drawings; 50 10 indicates the sheet that forms the envelop. Said sheet is cut and scored to provide a back wall 11, a front wall 12, end flaps 13 and a main flap 14. Said sheet is folded into the envelop form and the flaps 13 are 55 bent over and glued or otherwise attached

to the front wall 12 of the envelop in the usual manner. The envelop used to illustrate our invention, as will be apparent, is known as the "square fold" envelop.

Eyelet string fasteners are provided on 60 the front wall 12 of the envelop body and on the flap 14 respectively for securing the envelop flap in its closed position. 15 indicates a string fastener attached to the flap, and 16 and 17 indicate string fasteners attached to the front wall 12 of the envelop. 65 The string fastener 16 is so placed, that when the flap is closed upon the front wall of the envelop or when the flap is tucked within the envelop, it will coincide with the 70 position of the string fastener 15. All of said string fasteners are eyeleted to the envelop in a familiar manner, and while the fastener 16 is not used as an attaching means for the string, its eyelet provides 75 a reinforced hole through the front wall 12 of the envelop body for a purpose soon to appear.

A string 18 is permanently attached to the 80 fastener 15 on the flap 14 in the usual manner. When the flap is folded on the outside of the envelop, as illustrated in Fig. 1 and in Fig. 3, the string is wound about the fastener 17 in the usual fashion. An address 19 is printed on the outer face of 85 the flap so that when the flap is folded outside the envelop, this address will appear.

In this particular instance, the address is that of the freight auditor and the envelop would accordingly be forwarded to 90 him. A second address 20 as shown, that of the station agent, is printed on the face of the front wall 12 of the envelop in the space which is covered by the flap when the flap is folded without the envelop. As is 95 apparent from an inspection of Fig. 5 of the drawings these addresses are printed upon the same face of the sheet 10 that forms the envelop and may thus be printed at the same time, eliminating the necessity of two 100 printing operations upon the same envelop which obviously is quite expensive.

When the flap 14 is inserted within the envelop as indicated in Fig. 2, the string is passed through the reinforced hole provided by the eyelet which attaches the fastener 16 to the envelop and is then carried down and wound about the fastener 17 in the usual fashion. This securely closes the envelop with the flap inside and with the 110

address 20 on the front wall 12 of the envelop body disclosed to view so that the envelop will be accordingly forwarded to that particular station agent whose address 5 is thus disclosed.

A number of coinciding holes 21 are made in the front and rear walls of the envelop which provide means for inspecting the envelop to determine whether there is any- 10 thing within it, without the necessity of actually opening the same. These holes are provided because in the use of these envelopes by railroads, the station agent is required to send an envelop to the auditor 15 each day for purposes of record—even if he has nothing to send within the same—this being in the usual course or routine of railroads.

One of the advantages of our new construction resides in the fact that, in manipulating the flap to disclose either address, said flap is folded in the normal way and in the same direction only, in which it was intended to be folded and this fold is al- 25 ways along the same line. The result is that the life of the envelop in the frequent use to which it is put is greatly lengthened as compared with envelopes heretofore made for a similar purpose.

30 Another advantage of our improved envelop is that both addresses may be printed upon it by one printing operation, instead of two operations as has heretofore been necessary.

35 A further advantage of the construction

is that when the flap 14 is in the position disclosing either address there is simply the normal thickness of the envelop with its flap at the one edge; so that when the envelopes are assorted in piles as they are 40 in their use, they will lie flat and not tend to increase the thickness of the stack on the side next the flap.

We claim as our invention:

A return envelop comprising an envelop 45 body having front and rear walls and an opening at one edge, a flap connected to said rear wall and adapted to fold down upon the front wall or to be inserted into said opening between said front and rear walls, a string fastener and a string attached to the outer face of said flap, means providing a reinforced hole in said front wall at a point coinciding with the position of the string fastener on said flap when 50 in a folded position and a second string fastener upon the front wall of the envelop in a position below said flap when the same is in its folded position.

In testimony, that we claim the foregoing 60 as our invention we affix our signatures in the presence of two witnesses, this 26th day of June, A. D. 1916.
